United States Patent Office

Des. 194,755
Patented Mar. 5, 1963

194,755

CIGARETTE LIGHTER

Lee H. Pelzman, New York, N.Y., assignor to The Unilite Corp., New York, N.Y., a corporation of New York

Filed June 11, 1962, Ser. No. 70,502

Term of patent 3½ years

(Cl. D48—27)

FIG. 1

FIG. 2

FIG. 3

FIG. 4

FIG. 5

FIG. 6

FIG. 1 is a perspective view of a cigarette lighter showing my new design;

FIG. 2 is a side elevational view thereof;

FIG. 3 is an end view thereof;

FIG. 4 is a view of the other end thereof;

FIG. 5 is a top plan view thereof; and

FIG. 6 is a bottom view thereof.

I claim:

The ornamental design for a cigarette lighter, substantially as shown.
